UNITED STATES PATENT OFFICE.

SAM H. LIBBY, OF SCHENECTADY, NEW YORK, ASSIGNOR TO THE GENERAL ELECTRIC COMPANY, OF NEW YORK.

PNEUMATICALLY-OPERATED CONTACT-SHOE FOR ELECTRIC RAILWAYS.

SPECIFICATION forming part of Letters Patent No. 637,806, dated November 28, 1899.

Application filed September 20, 1897. Serial No. 652,238. (No model.)

To all whom it may concern:

Be it known that I, SAM H. LIBBY, a citizen of the United States, residing at Schenectady, in the county of Schenectady, State of New York, have invented certain new and useful Improvements in Pneumatically - Operated Contact-Shoes for Third-Rail Systems, (Case No. 578,) of which the following is a specification.

- 10 The present invention has for its object to provide a pneumatic control for the contact shoe or shoes of the well-known third-rail electric-railway system either for maintaining the shoes in contact with the contact-rail or 15 for lifting them from the contact-rail when for any reason this is desirable—as, for example, at the time when the vehicles of one system cross the tracks of another system or 20 switch from one track to another—thereby preventing the shoe or shoes from striking the traffic-rails and either short-circuiting the system or being torn from its fastenings.

In the accompanying drawings, Figure 1 is an end elevation of a car, showing my improved means attached thereto. Fig. 2 is a partial side view of a truck. Fig. 3 is an inverted plan view of a valve for controlling the operation of the shoe. Fig. 4 is a sectional view taken on line 4-4 of Fig. 3. Fig. 5 is a diagrammatic view of a track-section, showing the location of the valve-actuators; and Fig. 6 is a slight modification of the contact-shoe.

The body of the vehicle A is mounted upon a truck B of any desired construction. The latter is provided with wheels C, adapted to run on the traffic-rails D, which are supported by cross-ties F. The third or contact rail E is unsupported by insulators E', situated on each side of the web of the rail. The motor G is sleeved on one axle of the truck in the usual manner and is preferably spring-supported at the front end. Bolted to and extending rearwardly from the field-casting of the motor are brackets K, forming a support for blocks L, which support and insulate the contact-shoe M. Mounted upon and insulated from the brackets by blocks L is a casting R, having downwardly-extending forked ends, in which are mounted links b b, forming connections between the shoes M M' and castings R. In the present instance two contact-shoes

M and M' are shown, but in some cases one is sufficient. Secured to the adjacent ends of the shoes is an angular member provided with a lug which engages with the link N. 55 Situated on each side of cylinder J are links N, pivotally secured at their upper ends to cross-head J', carried by the end of the piston-rod. The lower end of each link N is slotted to permit the shoes to have a limited amount 60 of vertical play. Extending parallel with the contact-shoes are connecting-pieces R', slotted at their outer ends to receive lugs m m' on the shoes and provided in the center with lugs b', arranged to work in slots formed at 65 the lower end of links N. Bolted to the upper side of casting R is a cylinder J, provided with a piston for moving the cross-head J' up and down as air is admitted to the cylinder from pipes H and I. Placed upon the platform of the vehicle or other convenient spot 70 is a controlling-stand U, carrying at its upper end a valve which is provided with an operating-handle U'. The valve is connected with the cylinder J by pipes H I and with the source 75 of supply by pipe Z. I have shown the contact-shoes so arranged that they can be controlled by the controlling-stand U or by valve Q, located on the truck-frame; but it is within my invention to employ either or both of 80 the devices. The construction of the valves in both cases being the same, it will be described in connection with the automatic device. (Shown best in Figs. 3 and 4.)

The pipes H and I extend from the cylinder to valve Q, carried by some fixed portion of the truck. Valve Q has an operating-handle extending both sides of the valve-center and is adapted to engage with the actuating devices O and O', located at one side of the 90 track. The valve consists of a rectangular metal box having a central opening, in which is mounted a movable head Q', having suitable ports for controlling the admission of air to pipes H and I. Chamber Q² is connected with pipe Z, leading from the supply-tank Z', located in any convenient place on the vehicle. With the parts arranged as shown, air enters from pipe Z, passes through chamber Q² and opening Q⁴ to pipe I, and thence to 95 cylinder J, raising the piston and contact-shoes. Pipe H is open to atmosphere through 100

exhaust-pipe Y and passage Q³. (Shown in dotted lines in the head.) The valve is intended to move through an angle of approximately forty-five degrees, the extremes representing its two positions. When moved from the position shown to its other position, head Q' connects pipe I with exhaust-pipe Y by means of passage Q³, and chamber Q² is connected with pipe H through opening Q⁴.

10 The actuating devices O O' are located with respect to the valve as indicated in Fig. 3, O being situated at the left of the valve-center and O' at the right. The first one striking handle P moves it in one direction and the next one in the opposite. Under normal conditions the weight of the shoe is sufficient to establish good contact with rail E, and the air-pressure may be relieved from cylinder J by a suitable valve.

20 When the valve for controlling the admission of air to the cylinder is located on the platform, the arrangement of parts is the same as described, but, of course, the construction is much lighter.

25 The actuating device O consists of an arm pivoted to support O³. The latter is bolted to cross-tie F. To lessen the shock between the arm and handle, a spring O² is employed, which tends to hold the arm in the position shown.

30 Fig. 5 shows in diagram a section of track with the continuity of the third rail E interrupted and actuating devices O located in position to control the operation of the shoe-raising mechanism.

35 Compressed air for operating the shoes is obtained from the regular train-supply, which is connected to tank Z'.

The action of the invention when under 40 automatic control will now be described. Assume that the vehicle is advancing from left to right and that it is desired to raise the shoe or shoes while passing over the opening between the ends of the third rail E. Handle 45 P of the valve will strike the vertically-extending arm of actuator O and be rotated in a left-handed direction. This admits air from the source of supply to pipe I, which is connected to the bottom of cylinder J, and the 50 piston rises and lifts the shoes by means of links N. When the train advances to the farther end of the opening, valve-handle P will strike actuating device O' and valve Q will be moved to a point where the pipe I is open to the atmosphere and air under pressure admitted to cylinder J from pipe H.

55 For manually controlling the shoe-raising mechanism handle U' is employed, which actuates a valve similar in construction to valve Q. Both the automatic and manual control may be employed, if desired.

Under certain conditions where heavy currents are employed it is desirable to apply the contact-shoe to the rail or conductor E under 60 pressure. In Fig. 6 is shown a construction adapted for such use. Mounted within cylinder J is a piston, and secured to the end of

the piston-rod is a cross-head J', adapted to move in guides J², extending downward from the cylinder. The contact-shoe is removably secured to cross-head J' in any suitable manner. Pipes H and I convey the compressed air to and from the cylinder. By applying a moderate amount of pressure to the piston the contact-shoe will follow closely all the irregularities in the track and establish good connection therewith. In this manner I am enabled to dispense with all springs and connecting-links, at the same time maintaining good conductivity on the system.

80 What I claim as new, and desire to secure by Letters Patent of the United States, is—

1. The combination in an electric railway, with a traveling vehicle, of electric motors thereon, a contact-rail, a contact-shoe carried by the vehicle and adapted to make electrical connection between said rail and motors, and a pneumatic motor for moving the shoe out of contact with the rail.

2. The combination in an electric railway, with a traveling vehicle, of electric motors thereon, a contact-rail, a contact-shoe carried by the vehicle and adapted to make electrical connection between said rail and motors, a piston and cylinder for moving the shoe into and out of contact with the rail, and a valve controlling the operation of the piston.

3. In an electric railway, the combination of a traveling vehicle, a motor mounted on the truck, supports extending outwardly from the motor, a contact-shoe mounted thereon and adapted to make electrical connection between said rail and motors, a piston and cylinder for moving the shoe into and out of contact with the rail, and a valve controlling the operation of the piston.

4. The combination in an electric railway, of a traveling vehicle, electric motors thereon, a contact-rail, a contact-shoe carried by the vehicle and adapted to make electrical connection between said rail and motors, and a pneumatic device for maintaining the shoe in contact with the rail.

5. The combination in an electric railway, of a traveling vehicle, electric motors thereon, a contact-rail, a contact-shoe carried by the vehicle and adapted to make electrical connection between said rail and motors, a piston and cylinder carried by the vehicle, said contact-shoe being moved by the piston into and out of engagement with the contact-rail and adapted to be maintained in contact with the rail by fluid-pressure.

6. In an electric railway, the combination of a moving vehicle, a fixed conductor located along the line of travel, a contact-maker mounted on the vehicle, and adapted to make contact with the conductor, pneumatically-actuated means for moving the contact-maker into contact with the conductor and maintaining a certain pressure thereon, and a valve controlling the operation of the said means.

7. The combination with an electric vehi-

cle, of a contact-rail, a collector carried by the vehicle independently movable, and adapted to engage with said contact-rail, and a cushion composed of an elastic fluid adapted to 5 press said collector upon said contact-rail and to yield when the collector encounters irregularities of the contact-rail.

8. The combination with an electric vehicle, of a contact-rail, a collector carried by the 10 vehicle, independently movable and adapted to engage with said contact-rail, and means for lifting said collector from said rail and also maintaining it in its elevated position, by fluid-pressure.

15 9. The combination with an electric vehicle, of a contact-rail, a collector carried by the vehicle, independently movable and adapted to engage with said contact-rail, a motor on the vehicle for moving said collector, and 20 means along the way adapted to be engaged by the vehicle for controlling the operation of said motor.

10. The combination with an electric vehicle, of a contact-rail, an independently-movable 25 collector carried by the vehicle, a motor on the vehicle for moving said collector, and means along the way adapted to be engaged by the vehicle to cause the motor to elevate said collector and maintain it in its elevated 30 position.

11. The combination with an electric vehicle, of a contact-rail, an independently-movable collector carried by the vehicle, a motor on the vehicle for moving the collector, and 35 means along the way on opposite sides of an obstruction to the collector, adapted to be en-

gaged by the vehicle to cause the motor to move said collector in opposite directions.

12. The combination with an electric vehicle, of a contact-rail, an independently-mov- 40 able collector carried by the vehicle, and a motor on the vehicle adapted to move said collector from either limit of its movement and maintain it in its opposite position.

13. The combination with an electric vehicle, of a contact-rail, an independently-mov- 45 able collector carried by the vehicle, a motor on the vehicle for moving the collector from either limit of its movement and maintaining it in its opposite position, and means along 50 the way on opposite sides of an obstruction to the collector, adapted to be engaged by the vehicle to cause the motor to operate in opposite directions.

14. The combination with an electric vehicle, of a contact-rail, an independently-mov- 55 able collector carried by the vehicle, a pneu-
matic motor on the vehicle, and means along the way adapted to engage with the control-
ling-valves of the motor. 60

15. The combination with an electric vehicle, of a contact-rail, an independently-mov- 65 able collector carried by the vehicle, and a resiliently-mounted arm along the way adapt-
ed to cause the movement of said collector.

In witness whereof I have hereunto set my hand this 17th day of September, 1897.
